UNITED STATES PATENT OFFICE.

THOMAS K. HANSBERRY, OF NORTON, KANSAS.

DOOR-CHECK.

SPECIFICATION forming part of Letters Patent No. 404,038, dated May 28, 1889.

Application filed July 12, 1888. Serial No. 279,698. (No model.)

To all whom it may concern:

Be it known that I, THOMAS K. HANSBERRY, a citizen of the United States, residing at Norton, in the county of Norton and State of 5 Kansas, have invented new and useful Improvements in Combined Door Checks and Buffers, of which the following is a specification.

The invention relates to improvements in 10 combined door checks and buffers.

The object of the present invention is to produce a device of great simplicity and cheapness that will be capable of holding a door at any position, and that will also act as a buffer 15 and prevent the door coming in contact with the wall.

The invention consists in the novel combination and arrangement of parts hereinafter fully described, illustrated in the accompanying drawings, and pointed out in the claim 20 hereto appended.

In the drawings, Figure 1 is a perspective view of a combined door check and buffer constructed in accordance with this invention 25 and applied in position to a door. Fig. 2 is a similar view of the device itself.

Referring to the drawings, A designates a casing constructed of suitable material and designed to have pivotally secured within it 30 a lever, B. The casing A may be cast in one piece; but it is preferable to construct it of two pieces—the top plate, A', and the base-plate A², which plates are secured together and to a door, C, by screw D or other suitable 35 means of attachment.

The lever B is secured within the casing A by a pivot, E, which may, as illustrated in the accompanying drawings, be an ordinary screw, which will, besides performing the function 40 of a pivot, strengthen the parts and make them more durable. The lower portion, b, of the lever B is curved and provided upon its lower face with grooves or serrations to roughen it and produce a friction-surface, b', 45 to enable it to obtain a secure hold upon the floor, which it is adapted to engage to hold the door C and prevent its swinging. The friction-surface b' may be produced by notches, cross-grooves, or transverse grooves, and I desire 50 it to be understood that I do not limit myself to the precise details of construction herein

shown and described, as I may without departing from the spirit of the invention make any minor changes therein. The upper portion, b², of the lever B is straight, and is provided with a lateral projection, b³, which serves as a handle, whereby the lower end, b, of the lever is raised and brought out of engagement with the floor to permit the door C to be moved. The lower portion, b, of the lever B 55 is lifted up from the floor by placing the foot upon the projection b³ and pressing down, and the position of the door C may be instantly changed, and the lower portion, b, of the lever B is held normally raised from the floor 60 by the upper portion, b², which is sufficiently weighted to hold the lower portion, b, elevated when the lever B is thrown clear back, and the weighted upper portion then rests upon the casing, as is clearly illustrated in Fig. 1 65 of the accompanying drawings. 70

Besides serving as a handle to elevate and depress the lower portion, b, the projection acts as a buffer and prevents the door C coming in contact with the wall. 75

From the foregoing description and the accompanying drawings it will be readily seen that combined door checks and buffers constructed in accordance with this invention are capable of holding a door at any position and 80 of preventing the door coming in contact with the wall.

In practice the outer end of the projection b³ is covered with rubber, leather, or the like, as at b⁴, to more effectually serve the purpose 85 of a buffer.

The casing A is not essential, as I may pivot the lever directly to the door without employing a casing, the lever normally lying horizontally along the door; also, the lever B may 90 be made of any length desired; hence I do not wish to be limited to mere matters of size or proportion.

Of course I am aware that it is not broadly new to construct a door-check with a lever 95 having a curved lower end to engage the floor, and knobs or disks have been pivoted eccentrically to doors to accomplish the same result; but

What I do claim, and desire to secure by 100 Letters Patent, is—
A combined door check and buffer consist-

ing of a lever adapted to be pivoted centrally to a door and normally lie horizontally along the door out of contact with the floor, and having its lower portion curved and serrated and capable of engaging the floor and its upper portion straight and provided with a lateral projection, serving as a handle and a buffer, substantially as described.

In testimony that I claim the foregoing as my own I have hereto affixed my signature in presence of two witnesses.

THOMAS K. HANSBERRY.
